(57) **CLAIM**

The ornamental design for a tote, as shown and described.

DESCRIPTION

FIG. 1 is a top, perspective view showing an embodiment of a tote.

FIG. 2 is a left side elevation view thereof.

FIG. 3 is right side elevation view thereof.

FIG. 4 is a front side elevation view thereof.

FIG. 5 is a rear side elevation of view thereof.

FIG. 6 is a top view thereof; and,

FIG. 7 is a bottom view thereof.

The broken lines shown on claimed surfaces depict claimed stitching. The broken lines showing hardware and a zipper pull depict portions of the article and form no part of the claim.

1 Claim, 7 Drawing Sheets
